WIDE RANGE CENTRIFUGAL GOVERNOR

Filed May 15, 1942

UNITED STATES PATENT OFFICE

2,317,022

WIDE RANGE CENTRIFUGAL GOVERNOR

Walter E. Benjamin, Anderson, Ind., assignor to
 Pierce Governor Company, Anderson, Ind., a
 corporation

Application May 15, 1942, Serial No. 443,112

11 Claims. (Cl. 264—15)

This invention relates to a wide range governor suitable for Diesel engines and is associated more particularly with the fuel pump thereof and specifically the pump rack shaft.

This invention is directed to a combination idling and overspeed speed governor.

The chief object of this invention is to obtain fuel governing at idle speeds, full throttle control at speeds thereabove up to predetermined overspeed, and at that overspeed to automatically govern to prevent destructive and unauthorized engine speeds, the invention in the last instance giving the desired percent of regulation selected by the motor manufacturer.

One chief feature of the invention is the provision of dissimilar weight means, all weight means being operatively effective at idle motor speeds to insure adequate torque to properly actuate the pump shaft so that it is responsive to the slightest change in motor speed at low idle. Above the idle speed one weight means only remains operatively effective for overspeed control purposes, the other, or others, being locked out of operation whereby destructive weight forces are held to a minimum.

Two forms of dissimilar weight means are illustrated by way of example only.

Another chief feature of the invention is the toggle type connection between the main linkage of the governor and the over speed control lever and the peculiar action of the aforesaid throughout the range of governor operation to attain the objective specified, all as hereinafter set forth.

Other objects and features of the invention will be set forth more fully hereinafter.

The full nature of the invention will be understood from the accompanying drawing and the following description and claims:

In the drawing, Fig. 1 is a longitudinal sectional view through the governor. The section, however, is broken, that is, it is not taken in a single plane.

Fig. 1—A is an enlarged sectional view taken on line A—A of Fig. 1 and in the direction of the arrows.

Fig. 2 is a transverse sectional view through the governor. This section also is of broken character, and is of a left hand governor as distinguished from the right hand governor of Figures 1 and 3.

Fig. 3 is a similar longitudinal section but looking in the opposite direction.

Fig. 4 is a top plan view.

Fig. 5 is an elevational view of a modified form of dissimilar weight structure, parts being broken away to illustrate same and other parts in quarter section.

Fig. 6 is a similar view of the same embodiment but of a weight form included but not specifically illustrated in Fig. 5.

The dissimilar weight structures illustrated in Figs. 5 and 6 are also illustrated and described in copending allowed application Serial No. 306,653 filed November 29, 1939, now Patent No. 2,290,797 dated July 21, 1942, but not specifically claimed therein.

Reference is to be had to the aforesaid copending application for an understanding broadly of the connection of the governor illustrated herein, to a Diesel fuel pump for a Diesel engine or motor.

10 The housing in the present instance includes a bracket portion 10 with a flange 10a. This forms the end of the housing that is secured to the fuel pump. It has an opening 11 which is in alignment with the pump rack shaft. It also has an opening 12 that receives a shaft that extends into the bracket portion 10 that closes the body portion 13 of the governor housing.

15 A gear 14 is suitably connected to the pump drive shaft or an equivalent shaft, and this gear 14 meshes with a pinion 15 carried by a speed shaft 16 mounted in bearings 17 and 18 at opposite ends of the governor housing structure. A cap 19 closes the top of the housing. This cap also mounts a short shaft 20 which externally

20 mounts a lever 21, same being the shutoff lever. Internally said short shaft mounts an arm 22 that is adapted to be associated with a lug 23 carried by the member 24 pivotally connected at 25 to the main operating lever 26 of the control linkage.

25 The portion 24 is internally threaded to receive the threaded end of a rack shaft connecting member 27 and the same is adjustably associated therewith as well as rigidly associated therewith by said nut 28. The portion designated by the

30 numeral 29 is the "smoke" stop structure and the same is arranged as at 30 for connection to the pump rack shaft. A nut 31 is also mounted on the threaded member 27 and it and the member 45 are radially drilled to receive a wire 32 that is adapted to pass through an aperture 33 on a locknut 34 of the "smoke" stop structure. A lead seal 35 secures the ends of the wires together; hence, the smoke stop adjustment cannot be 50 changed without destroying the seal arrangement, thereby insuring against tampering without indicating subsequent adjustment.

The lever 26 is pinned as at 36 to a shaft 37. This shaft 37 is rotatably supported in bearings 38 spaced apart and each being pinned as at 39

to a parallel shaft 40. This shaft 40 is rotatably supported in bearings 41 at opposite sides of the governor housing and one end of the shaft 40 projects therefrom as at 42 and mounted thereon is the throttle lever 43. Note the shaft 37 is not pinned to the bearing elements 33.

Since shaft 40 is the throttle shaft, there is provided—see Fig. 1—an adjustable stop 43a, same being adapted for engagement to limit lever arm movement 26 and this is the wide open throttle adjustment. Floating on the shaft 40 is a spring loaded lever 44 having a tail portion 45 adapted to engage an adjustable stop 46 in the base of the governor housing. The upper end of this L-shaped lever 44 has an angular extension 47 about which is coiled one end of a load spring 48. The other end of the load spring is receivable by the recessed threaded member 49, the same being threaded into the aperture 50 and locked in longitudinal adjusted position by the locknut 51. This adjustment last mentioned is the high speed setting and is usually sealed by the motor manufacturer after the engine has been tested and the governor has been associated therewith under test and said sealing arrangement may be of a similar character to that previously described for the "smoke" stop sealing arrangement.

Referring more particularly to Figs. 2 and 3, it will be noted that the end of the shaft 37 is threaded as at 52 and mounted therein is the threaded end 53 of an eye structure 54 that mounts one end 55 of the idle adjustment structure. The spring 56 has its opposite end 57 connected to the rotatable member 58 carried by the member 59 in turn supported as at 60. The idle adjustment structure is indicated broadly at 61 and in this manner the position of the member 59 or more particularly the member 58, may be moved toward and away from the end of the governor housing that mounts the load spring. The actual distance of the spring 56 may be adjusted by turning the member 58 in the member 59. Turning it to the right or clockwise will cause the member 53 to thread down into the shaft 37. This stretches the spring 56 and makes the device more sensitive at idle speeds. Turning this member 58 to the left elevates the anchorage 53 relative to the shaft 37 and thus permits the spring to have less tension and accordingly, the adjustment is of more stable character. It is preferred that the adjustment be such that but little, if any, surge in the governor at idle speed will occur.

Reference now will be had more particularly to the speed responsive shaft and the weight mechanisms associated therewith. Pinned to the speed shaft 16 as at 62 is a base structure 63 which herein is shown provided with two pairs of spaced ears 64 and in the same is mounted the shafts 65. Mounted on each shaft 65 are two dissimilar weights, one being indicated by the numeral 66, same being the short-nose weight, and the other being indicated by the numeral 67, same being the long-nose weight. Both weights are coaxially mounted on the same shaft. The masses of these weights are different. Preferably the two short-nose weights are mounted, as it were, in diametrical relation relative to the shaft 16 and in like manner, the long nose weights are similarly mounted relative thereto, same being for better balance.

Rotatably and slidably supported on the shaft 16 is a sleeve 70. This sleeve 70 is reduced as at 71 to provide clearance for the weight struc-

tures pivoted on shafts 65. In other words, the weight portions when the weights are collapsed do not engage the sleeve 70 when the shaft 16 is rotated at a speed below that at which centrifugal force becomes operative to move the weights outwardly.

The sleeve 70 mounts an anti-friction collar arrangement 72 and this collar normally bears against the bifurcated portions 73 of the member 74 which is mounted on shaft 37 and which portions straddle shaft 16.

The weight outlines and particularly the lengths of the noses is shown in Fig. 1, the noses being indicated by the numeral 66a and 67a. It will also be observed that these weights have tail portions 66b and 67b, respectively. As shown in Fig. 1, the short nose weights have moved outwardly responsive to centrifugal force by pivoting on the shafts 65 and their noses 66a have advanced as far as possible toward the anti-friction structure 72, such advance movement being limited by stop 66b.

It will be apparent then that the weights 66 can move outwardly no farther despite any increase in speed of shaft 16. However, weights 67 can move outwardly further and will do so as speed increases until their tail portions or stops 67b also engage the base structure and further outward movement is prevented. Between these extreme positions the long nose weights are effective for additional longitudinal travel of sleeve 70 on the shaft 16. Thus, at low speeds both weights move outwardly under centrifugal force until the short nose weights are prevented from further outward movement. Thereafter the long nose weights continue further outward movement until they in turn are prevented from further outward movement.

Referring to Figs. 2 and 1, it will be noted that the lever 44 floatingly mounted on the shaft 40 has a branch 75 and extending forwardly from the branch 75 and the lever 44 are the spaced abutments 76. These abutments lie parallel to the shaft 16 and in effect are positioned at opposite sides thereof as shown by dotted lines in Fig. 2. The forward ends of these abutments 76 are adapted to be engaged by the portions 73 of the bifurcated lever 74, when the sleeve 70 is moved toward the lever 44 under the influence of the long nose weights. Normally at no load and with the weights collapsed, there is approximately $\frac{1}{4}$ " difference or clearance between the parts 73 and 76. Hence, all the low speed or idle speed ranging is accommodated in this $\frac{1}{4}$ " travel of the sleeve 70 and the opposing force is that exerted by the spring 56, having the several adjustments previously mentioned. The high speed or overspeed range of the governor is accommodated by the load spring 48 also adjustable. It is to be observed that the stop 46 limits the permissible movement of the lever 44 toward the weights and in this manner the gap between the parts 73 and 76 may be accurately adjusted.

Referring to Fig. 4, it will be observed that clockwise rotation of the lever 21 will result in similar movement of member 22 and reverse movement will result in the member 22 picking up the abutment or lug 23 and moving the pump shaft to closed position. It will also be noted that the $\frac{1}{4}$ " travel range is ample for idle regulation, and that the weight arrangement is such that by reason of its balanced construction, that destructive forces incident thereto are reduced to a minimum. Furthermore, this gov-

ernor structure permits operative or manual control of the fuel pump through the throttle lever 43 illustrated, or any other convenient throttle structure connected to shaft 42 and external of the governor housing.

One peculiarity of operation will now be set forth as follows: With lever 44 in the position shown in Fig. 1 and the members 38 in similar position it is quite evident that there is no load in starting position. As the weights move out under the action of centrifugal force, the sleeve 70 will move to the right on shaft 16 and cause the bifurcated structure 74 to tilt clockwise around the axis of shaft 37, and since structure 74 is secured to shaft 37 at 74a, the lever 26, also secured thereto, will also tilt clockwise, thus reducing the fuel supply.

When this action has been accomplished, further movement of the sleeve 70 toward the right in Fig. 1, will pick up lever 44 and move the latter in opposition to the force exerted by the load spring 48. At the same time the entire structure has moved about the axis of shaft 40 and not about the axis of shaft 37. Thus, the result is a transference of pivotal action from one shaft center to the other shaft center.

With this form of the invention, the engine starts at full fuel position of the throttle arm 43. As the engine speeds up under idle conditions, the lever 26 tilts clockwise—see Fig. 1—which pulls back on the fuel rod. This continues until contact with lugs 76 is obtained. Further sleeve travel then causes movement of lever 44 but in so doing the previous toggle structure breaks back to its original condition and in so doing the rack shaft arm rod is pushed out to its original position and when this has occurred the governor takes over for high speed or overspeed control. It will be noted that the shaft 37 moves clockwise toward the stop 43 and in so doing, under normal conditions, sufficient clearance is provided to insure governor operation for high speed control. The adjustment effected by the nut 34 is in accordance with the R. P. M. desired.

Reference now is had to the upper left hand portion of Fig. 1 and Fig. 1—A relative to the smoke stop structure. The sleeve 129 contacts the face of the Diesel pump at full load speed. The amount of full fuel is set by adjustment of part 139 and is locked by nut 28. The pump fuel metering rack shaft 131 is attached to part 139 by means of the floating pin 30, which allows the whole assembly to oscillate through the arc of travel of the governor lever. The balance of the assembly is essentially a linkage adjustment that is necessary in any governor connection to a pump.

By using twenty threads per inch on sleeve 129 and portion 29 of member 139, it is evident that one complete rotation of the sleeve will advance this part .050 inch; by further placing ten equally spaced marks on the bevel of the sleeve, this .050" can be further equally divided to increments of .005", making possible a micrometer adjustment for a smoke stop.

All this makes it possible for an engine manufacturer to predetermine the correct position of the smoke stop on the engine and eliminate a lot of "cut and try" experimentation.

Referring to Figs. 5 and 6, herein the governor mechanism, other than the centrifugal weights, the base support therefor, the noses and tails thereof and the longitudinal slideable and rotatable sleeve, is omitted. This form of the inven-

tion differs from that illustrated in the preceding figures in that herein four weight supporting shafts are provided and upon two parallel shafts are mounted the short nose weights and upon two other parallel shafts transverse to the first mentioned shafts, are mounted the long nose weights. Numerals similar to those utilized heretofore to designate like or equivalent parts in Figs. 1 to 4, inclusive, but increased by one hundred, are utilized to designate like or similar parts in Figs. 5 and 6.

As previously set forth, there are four weights disclosed in both embodiments of the invention but in the first embodiment two shafts only are utilized while in the second embodiment, four shafts are utilized and in this connection the weights of the same type are in each instance positioned diametrically opposite each other, there being but two of each type utilized in the centrifugal part of the mechanism.

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a governor for Diesel engines having a fuel pump with a control member, the combination of a plurality of dissimilar weight means, a shaft responsive to engine speed for rotating said means to subject same to centrifugal force, a control member subject to weight means movement under centrifugal force, a lever operatively interposed between said control members, means normally constraining the lever to predetermined position in opposition to said weight movement, another lever, means normally constraining same to predetermined position, said second lever being responsive to the centrifugal movement of one of the weight means, following the preceding lever response, and means operatively connecting both levers together for first mentioned lever operation initially independent of the second mentioned lever and conjoint operation.

2. In a governor for Diesel engines having a fuel pump with a control member, the combination of a plurality of dissimilar weight means, a shaft responsive to engine speed for rotating said

means to subject same to centrifugal force, a control member subject to weight means movement under centrifugal force, a lever operatively interposed between said control members, means normally constraining the lever to predetermined position in opposition to said weight

movement, another lever, means normally constraining same to predetermined position, said second lever being responsive to the centrifugal movement of one of the weight means, following

the preceding lever response, and means operatively connecting both levers together for first mentioned lever operation initially independent of the second mentioned lever and conjoint operation, said connecting means having a toggle type arrangement therein.

3. In a governor for Diesel engines having a fuel pump with a control member, the combination of a plurality of dissimilar weight means, a shaft responsive to engine speed for rotating said

means to subject same to centrifugal force, a

control member subject to weight means movement under centrifugal force, a lever operatively interposed between said control members, means normally constraining the lever to predetermined position in opposition to said weight movement, another lever, means normally constraining same to predetermined position, said second lever being responsive to the centrifugal movement of one of the weight means, following the preceding lever response, and means operatively connecting both levers together for first mentioned lever operation initially independent of the second mentioned lever and conjoint operation, said connecting means comprising a floating axis shaft, a fixed axis shaft, one shaft supporting one lever and the other shaft supporting the other lever, and arm means therebetween pivotally mounted on one shaft and fixed to the other shaft.

4. In a governor for Diesel engines having a fuel pump with a control member, the combination of a plurality of dissimilar weight means, a shaft responsive to engine speed for rotating said means to subject same to centrifugal force, a control member subject to weight means movement under centrifugal force, a lever operatively interposed between said control members, means normally constraining the lever to predetermined position in opposition to said weight movement, another lever, means normally constraining same to predetermined position, said second lever being responsive to the centrifugal movement of one of the weight means, following the preceding lever response, and means operatively connecting both levers together for first mentioned lever operation initially independent of the second mentioned lever and conjoint operation, said connecting means comprising a floating axis shaft, a fixed axis shaft, one shaft supporting one lever and the other shaft supporting the other lever, and arm means therebetween pivotally mounted on one shaft and fixed to the other shaft, the floating axis shaft being rigid with the first mentioned lever.

5. In a governor for Diesel engines having a fuel pump with a control member, the combination of a plurality of dissimilar weight means, a shaft responsive to engine speed for rotating said means to subject same to centrifugal force, a control member subject to weight means movement under centrifugal force, a lever operatively interposed between said control members, means normally constraining the lever to predetermined position in opposition to said weight movement, another lever, means normally constraining same to predetermined position, said second lever being responsive to the centrifugal movement of one of the weight means, following the preceding lever response, and means operatively connecting both levers together for first mentioned lever operation initially independent of the second mentioned lever and conjoint operation, said connecting means comprising a floating axis shaft, a fixed axis shaft, one shaft supporting one lever and the other shaft supporting the other lever, and arm means therebetween pivotally mounted on one shaft and fixed to the other shaft, the arm means being rigid with the fixed axis shaft.

6. In a governor for Diesel engines having a fuel pump with a control member, the combination of a plurality of dissimilar weight means, a shaft responsive to engine speed for rotating said means to subject same to centrifugal force, a control member subject to weight means movement under centrifugal force, a lever operatively interposed between said control members, means normally constraining the lever to predetermined position in opposition to said weight movement, another lever, means normally constraining same to predetermined position, said second lever being responsive to the centrifugal movement of one of the weight means, following the preceding lever response, and means operatively connecting both levers together for first mentioned lever operation initially independent of the second mentioned lever and conjoint operation, said connecting means comprising a floating axis shaft, a fixed axis shaft, one shaft supporting one lever and the other shaft supporting the other lever, and arm means therebetween pivotally mounted on one shaft and fixed to the other shaft, the floating axis shaft being rigid with the first mentioned lever and the arm means being rigid with the fixed axis shaft.

7. A governor as defined by claim 1, characterized by the dissimilar weight means comprising a plurality of pairs of weights, the weights of each pair being substantially identical and diametrically positioned relative to the axis of weight rotation, same being transverse to the pivotal axis of each weight.

8. A governor as defined by claim 1, characterized by the dissimilar weight means comprising a plurality of pairs of weights, the weights of each pair being substantially identical and diametrically positioned relative to the axis of weight rotation, same being transverse to the pivotal axis of each weight, one pair being of long nose character and another pair being of short nose character.

9. A governor as defined by claim 1, characterized by the dissimilar weight means comprising a plurality of pairs of weights, the weights of each pair being substantially identical and diametrically positioned relative to the axis of weight rotation, same being transverse to the pivotal axis of each weight, one pair being of long nose character and another pair being of short nose character, the long nose weights each having the greater total mass.

10. A governor as defined by claim 1, characterized by the dissimilar weight means comprising a plurality of pairs of weights, the weights of each pair being substantially identical and diametrically positioned relative to the axis of weight rotation, same being transverse to the pivotal axis of each weight, all dissimilar weights being pivotally mounted on a common axis.

11. A governor as defined by claim 1, characterized by the dissimilar weight means comprising a plurality of pairs of weights, the weights of each pair being substantially identical and diametrically positioned relative to the axis of weight rotation, same being transverse to the pivotal axis of each weight, each weight being pivotally mounted upon an individual axis, axes of like weights being parallel with the rotation axis therebetween.

WALTER E. BENJAMIN.
